UNITED STATES PATENT OFFICE

PHILIP L. MCKEE, OF CHICAGO, ILLINOIS

BUILDING CONSTRUCTION

Application filed December 19, 1927. Serial No. 240,988.

My invention relates to building constructions and particularly to the construction of the ridge pole of a greenhouse.

One of the objects of my invention is to provide a more compact and sturdy ridge pole construction by the use of a metallic I-beam in place of the heretofore used rectangular wooden beam disposed immediately beneath the ridge pole cap, which construction, because of the thickness of the web of the I-beam, permits the window sashes which are hinged to the ridge pole cap, to be more securely fastened to this I-beam while at the same time insuring a greater overlap of the ridge pole cap on the upper surfaces of these window sashes, thereby positively precluding the leakage of water into the greenhouse at the junction of the ridge pole and the hinged window sashes.

Still another object of my invention resides in the utilization of a metallic I-beam as the main member of the ridge pole which provides a better support for the swinging window sashes, and also permits of the utilization of a narrower ridge pole cap to which the swinging window sashes are hinged while at the same time permits the ridge pole cap to be more securely attached to the I-beam.

These and other objects of my invention will be apparent from a perusal of the following specification when taken in connection with the accompanying drawings, wherein:-

Figure 1 is a side view partly in section, of my improved construction.

Figure 2 is a plan view of the same with certain parts broken away.

Figure 3 is a cross sectional view directly through the ridge pole construction, and

Figure 4 is a section on line 4—4 of Figure 3.

Referring now to my improved greenhouse construction, it will be seen that the greenhouse or other structure comprises the vertical walls 2, which in the present instance are provided with the usual transparent panes, and the upwardly inclined roof beams 4, preferably of metal. These

roof beams 4 are bolted or riveted, as at 6, to a metal cap 8 which cap and a central support 10 are bolted and carried by the vertical pole-like support 12 in turn supported from supports 13 mounted on the ground or floor of the building, the supporting piece 10 has a horizontal flange to which is bolted or riveted, as at 14, the preferably metallic I-beam 16. The cross sectional shape of the upper portion of this beam 16 is of particular use and advantage as a means for supporting the swinging window sashes and ridge pole cap of my present construction.

As clearly shown, this I-beam 16 has a very thin web which terminates at its upper end in a relatively thick flange 18 having opposed portions. The ridge pole cap 20, preferably of wood, overlaps and is supported upon this flange 18, being secured thereto as by means of screws 22. The underside of this ridge pole cap is cut away as at 24, to permit the entry of the opposed window sashes 26 and 28 which are hinged, as at 30 and 32, to the opposed sides of the ridge pole cap 20 and to the upper faces of these window sashes 26 and 28. These window sashes carry the usual transparent panes 34 and 36 and are adapted to swing outwardly to permit the ingress of fresh air into the greenhouse or other structure, there being suitable lever connections 38 for operating these windows to open and close them. In addition, I provide additional window sashes 40 and 42 which form no part of the present invention, since the details of the manner of constructing my greenhouse with the pairs of windows 34 and 40 and 36 and 42 arranged on opposite sides of the ridge pole and operating to admit fresh air to the upper portion of the greenhouse, are covered in a co-pending application filed concurrently with this case. The present case relates to the details of construction of the ridge pole itself and the manner in which the windows 34 and 36 are hingedly connected thereto so as to swing to open and closed position.

It will be noticed that the inner ends of the sashes 26 and 28 are suitably cut away

or chamfered, as at 44, so as to permit these sashes to swing about their hinged pivots 30 free of the bolts or rivets 14, thereby permitting the doors to move freely upwardly 5 to open position. By reason of this very compact construction, I am enabled to bring the inner pivoted ends of these sashes 26 and 28 well beneath the ridge pole cap 20 so that by reason of this pronounced overlap, 10 any danger of water leaking through the hinged joint and into the greenhouse is eliminated. At the same time by reason of this thinness of the web 16, not only is this pronounced overlap made possible, but also 15 the ridge pole cap 20 need not be as wide as heretofore, since the chamfered ends of the sashes are brought closer together. In addition, by use of the I-beam 16, a much more sturdy construction is possible, since it per- 20 mits of the use of a relatively broad flange 18 with a thin web portion and similarly relatively broad lower flange 11 mounted on the horizontal flange of the support carried by the pole 12. The advantages of this 25 construction are apparent when it will be remembered that the need of a very sturdy mounting or ridge pole construction is necessary, because the sashes 26 and 28 are hingedly connected thereto. This construction, 30 while demanding the utmost rigidity and strength, must be also practically water tight, so that the rain is not able to leak into the greenhouse or building at the hinged junction of these sashes 26 and 28, and this 35 is accomplished by the pronounced overlap of the relatively narrow ridge pole cap 20 which in turn is made possible by the use of the metallic I-beam having the thin web portion which permits the inner ends of the 40 sashes to be brought very close together and well beneath the underside of the flange portion 18 of the I-beam, so that when in closed position, the chamfered edges of these sashes will snugly rest not only against the 45 sides of the web portion of the beam, but against the under surfaces of the flange 18 forming a leak-proof and weather proof joint at this point.

Having thus described my invention what 50 I claim as new and desire to secure by Letters Patent is:

1. In a ridge pole construction for a greenhouse, in combination with the upwardly inclined roof beams, a metallic cross beam supported at the upper ends of said converging beams having a thin web and a transversely extending upper flange providing opposed over-hanging portions, a ridge pole cap overlying and secured to 55 said flange of the cross beam with the outer portions of the cap overlying and slightly overhanging the opposed ends of said flange, a hinge secured to each opposed lateral wall of said cap with the pivotal axis of said 60 hinge at the lowermost edge of said cap, 55

a sash having its upper face secured to the lower leaf of said hinge, whereby said sash, when in closed position, engages the under side of said flange and the vertical wall of said web of the cross beam. 70

2. In a greenhouse construction, the combination of a central support and upwardly inclined roof beams connected to said support, a metallic I-beam mounted on said support and roof beams, a ridge pole cap 75 secured to the upper flange of said I-beam so as to overlie and slightly overhang the opposed ends of said flange, a hinge secured to each lateral wall of said cap with the pivoted axis thereof at the lowermost edge 80 of said cap, and a window sash having its upper face secured to the lower leaf of said hinge, the corners of the window sash at the hinged end being chamfered so as to present bearing surfaces 85 to engage the lower flange surface and web surface of the I-beam, whereby said sash is adapted to snugly fit within the corner of the I-beam presented by the flange and web thereof so as to positively prevent the leak- 90 age of water through the hinged structure. 90

In witness whereof, I have hereunto subscribed my name.

PHILIP L. McKEE.
